JOSEPH H. KAISER, OF BROWNSVILLE, PENNSYLVANIA.

SPECIFICATION forming part of Design No. 21,054, dated September 22, 1891.

Application filed July 13, 1891. Serial No. 399,434. Term of patent 7 years.

To all whom it may concern:

Be it known that I, JOSEPH H. KAISER, a citizen of the United States, residing at Brownsville, county of Fayette, State of Pennsylvania, have invented and produced a new and original Design for Spoons, of which the following is a specification, reference being had to the accompanying drawing, forming a part thereof.

10 The accompanying figure of drawing is a face view of a spoon, showing my design.

The leading feature of my design consists in a picture of the house in which Hon. James G. Blaine was born, the picture of the 15 said person, and a keystone.

A designates a spoon having in the bowl B thereof a true representation of the house at

Brownsville, Pennsylvania, which was the birthplace of Hon. James G. Blaine. The upper portion of the handle C is shown as 20 ornamented, and said handle is surmounted by a keystone D, having therein a picture of the person above named.

What I claim is—

The design for spoons, substantially as 25 herein shown and described.

In testimony that I claim the foregoing I hereunto affix my signature this 8th day of May, A. D. 1891.

JOSEPH H. KAISER. [L. S.]

In presence of—

CHARLES LARGE,
M. E. HARRISON.
